*Adam Hampton
Fire Place Grate
Patented May 15 1847*

Des. 122

Adam Hampton, New York, New York,
Letters Patent (Design No 122) dated 15th May 1847.

The schedule referred to in these Letters Patent and making
part of the same.

To all whom it may concern:—Be it known, that I, Adam Hampton, of the City of New York, in the County & State of New York, have produced a new design, to be cast in metal, for a "Summer Piece" of a fire place grate, and I do hereby declare that the following is a full, clear and exact description of the same, reference being had to the annexed drawings, making a part of this specification.

I provide a pattern of the following combination of figures, the two sides, right and left from the centre, corresponding one with the other. At the top, in the centre is a face (a) upon each side of which is a curved scroll; from this scroll extends a moulding known as (C) (D,) to the full width and closing upon the ground work; immediately over the extreme end of this moulding is an ornamental piece of

of scroll work (b). Near the outside of the sides and immediately under the above part last described, is a dome or recess, for a small ornamental ~~to stand in~~ or otherwise known as (e); immediately below is a cap piece of a column which forms a base for the dome, the cap is known as (g); (h) is still below this, and is an ornamental pillar and based upon a base surrounded by ornamental shell scrolls which are known as (i) and terminates by a finishing piece of scroll work (j) corner piece of ornamental ground and molding fills the corner between the top and side ornaments already described, and may be known as (f). In the centre near the base is a series of twisted scrolls running from the centre piece of shells, the whole being known as (m). This completes the ornate frame or outside part.

The centre piece is separate from the above and may be used singly in combination with the above frame. It consists of a recess for an ornament or statue, having a pedestal at the bottom; this recess may be known as (o) (p, p) are ornamental scrolls and paw up to the full top behind the scrolls surrounding the face upon the outer frame; these scrolls (p) form a full top or dome in half, for the centre piece. From its two extremes hang, or are attached the pillars (s) and these are connected by small scalloped ornaments upon which they stand upon the back ground (t). At the top of these last named pillars are the angular cap pieces, (n) and immediately below these caps are the circular caps (v).

Thus the centre piece is to correspond and match with the outer frame the whole making up a complete "Summer Piece" Design of ornaments of the Romanesque order of Architecture, and may be used to match with a variety of frames of grates to good advantage. The face (a) being cast in a separate piece it may be left off of the other part of the design without injury, and may sometimes be preferable.

Having thus fully described my design, what I claim as my production is the peculiar forms, shapes and figures making up this design for a "Summer Piece" for a fire place.
